UNITED STATES PATENT OFFICE

EDWARD I. FELTON, OF LITTLE ROCK, ARKANSAS

DESIGN FOR A CAFÉ BUILDING

Application filed February 1, 1929. Serial No. 29,873. Term of patent 14 years.

To all whom it may concern:

Be it known that I, EDWARD I. FELTON, a citizen of the United States of America, and a resident of Little Rock, in the county of Pulaski and State of Arkansas, have invented a new, original, and ornamental Design for a Café Building, of which the following is a specification, reference being had to the accompanying drawing, forming part thereof.

I claim:

The ornamental design for a café building, as shown.

EDWARD I. FELTON.
